UNITED STATES PATENT OFFICE.

EDWARD JOHN O'NEILL, OF ADA, OHIO.

RAILROAD-CROSSING.

SPECIFICATION forming part of Letters Patent No. 712,404, dated October 28, 1902.

Application filed June 16, 1902. Serial No. 111,925. (No model.)

To all whom it may concern:

Be it known that I, EDWARD JOHN O'NEILL, of Ada, in the county of Hardin and State of Ohio, have invented a new and useful Improvement in Railroad-Crossings, of which the following is a specification.

My invention is an improvement in railroad-crossings, having for an object, among others, to provide a simple construction whereby there is furnished a continuous track in one or the other direction of the crossing by means of swinging rail-sections and by which the swinging rail-sections are locked in their different adjustments; and the invention consists in certain novel constructions and combinations of parts, as will be hereinafter described and claimed.

In the drawings, Figure 1 is a top plan view of a crossing embodying my invention. Fig. 2 is a detail top plan view of the turn-table for the swinging rail-section. Fig. 3 is an end view of such rail-section in place in its turn-table. Fig. 4 is a top plan view. Fig. 5 an edge view, and Fig. 6 is a sectional view, 25 of the seat-plate for the turn-table. Fig. 7 illustrates in detail one of the pivot-stands for the horizontally-rocking lever. Fig. 8 illustrates in detail one of the guides for the slide-rods. Fig. 9 illustrates in detail one of 30 the pitmen connected with the cam-frames. Figs. 10, 11, and 12 illustrate in side view, respectively, the operating-cam. Fig. 13 illustrates the pivot-shaft for such cams. Fig. 14 is a top plan view, and Fig. 15 a sectional 35 view, of the seat-plate for the fixed sections, and Figs. 16 and 17 illustrate in detail the sliding lock. Fig. 18 is a sectional view on about line 18 18, Fig. 12; and Fig. 19 is a detail cross-section on about line 19 19 of Fig. 1.

40 By my invention I seek to dispense with the breaks in the rails which occur at a railroad-crossing, such as are now commonly in use, and thus avoid the blows of the wheels, which result in much damage not only to the rails and wheels, but to other portions of the cars, and by avoiding this I also avoid the noise resulting from the pounding of the rails, dispense with the necessity of constantly tamping beneath the crossing, especially in the 45 wet season, and relieve the passengers of the jolting resulting from the pounding as now commonly experienced.

As shown in Fig. 1, the tracks cross each other, the rails A of the track leading from right to left, crossing at a right angle the line 55 of the rails B, as shown. The pair of tracks crossing each other have the fixed rail-sections terminating on opposite sides of the point of crossing, and swinging rail-sections C are pivoted centrally between their ends 60 within the center of the space between the adjoining ends of the fixed rails, so the swinging rail-sections can be turned into alignment with the rails A or the rails B. The fixed rail-sections have their ends adjacent to the 65 crossing curved on concave lines 1, while the ends of the swinging rail-sections C have their ends curved on convex lines 2, so they will fit and conform to the concave ends 1 when turned into alignment therewith, as shown in 70 Fig. 1.

I will first describe in detail the construction at the crossing of one rail by another, as all the crossings are alike, and will then describe the means for shifting the swinging 75 rail-sections and for swinging the locking devices.

At its end adjacent to the crossing each fixed rail-section is seated on a chair-plate D, having a wing D' to overlie the base of the 80 rail and provided in its end away from the crossing with a dovetail groove D² to receive the rib E² on the sliding lock-plate E, presently described. The flange D' not only overlies and braces the fixed section, but also 85 forms a stop for the swinging rail-section when adjusted into alignment with the fixed rail-section. The locking-plate E is held by bolts E' slidably to the fixed rail-section and is movable longitudinally along the chair-plate 90 D, with its rib E² operating in the groove D² to position where it will overlap the end of the swinging rail-section when such swinging rail-section is in a line with the fixed rail or back away from the crossing to clear the swinging rail-section, as may be desired. This sliding lock-plate is operated by the means presently described.

The swinging rail-section C is held in a clamp F' on the upper side of the turn-table 100 F, which turn-table has its base F² circular and tapered, as shown in Fig. 3, and is provided on its under side with a central stud F³, as shown in Fig. 3. The turn-table base G is

composed of two sections G', combining to provide the circular undercut seat G² for the tapered base F² of the turn-table F and the circular socket G³ for the pivot-stud F³, the turn-table F fitting and turning within the base G in the operation of the device, as presently described.

For swinging the rail-sections C from one position to the other I employ longitudinally-movable slide-rods H, which are connected by pitmen H' with the turn-tables and when moved in one direction swing the rails of such turn-tables into alinement with the rails A and when moved in the opposite direction swing the rails C into alinement with the rails B. These slide-rods H are shown as extending parallel with the rails A and are connected at one end with cranks I on the shaft I, which is also provided with a crank I², which is connected by a pitman I³ with an operating cam-frame Y, as shown in Fig. 1. Alongside the same frame Y are arranged and operate cam-frames X and Z. The cam-frames X and Z operate the sliding lock-plates. To this end I provide a pitman J, connecting the cam-frame Z with the crank K' on a shaft K, which shaft is also provided with a crank K², connected by pitman K³ with a slide-rod L. This slide-rod L operates bell-crank levers M, which in turn operate slide-rods N, which extend parallel with the rails B and are connected by levers O and P with the lock-plates operating upon the fixed sections of the rails B. The levers O engage at one end with their respective lock-plates and at their other ends directly with the slide-rods N. The levers P connect at one end with their sliding lock-plates and at their other ends with short slide-rods P', whose other ends connect by levers P² with the slide-rod N, this construction operating to cause the locking-plates of the rail-sections B on opposite sides of any crossing to be moved toward or from each other, according to the direction of movement of the slide-rod N. The cam-frame X is connected by a pitman J' with a crank Q' on a shaft Q, such shaft being also provided with cranks Q², connected by pitmen Q³ with slide-rods R, which are connected by means of levers and slide-rods S, T, T', and T², corresponding to levers O P, slide-rod P', and lever P², before described, with their respective sliding lock-plates, so the movement of the slide-rods R will operate the sliding lock-plates operating in connection with the rail-sections A, as will be understood from the foregoing description. Guides 3, as shown in Fig. 8, are provided for the several slide-rods, and pivot-stands 4, as shown in Fig. 7, are supplied for the rocking levers. The cam-frames are fixed on a shaft U, so they will turn therewith, and are spaced apart by means of collars U' on such shaft, and the shaft is provided with a lever U², so the shaft may be turned to swing the cam-frames to different positions. Each cam-frame has a portion or portions curved on an

are struck from its center and an eccentric or cam portion or portions, as will be understood from Figs. 10, 11, and 12. Thus the cam-frame X has portions X' and X², formed on circular lines, and a portion X³, which operates as a cam to push or pull the pitman J', and thus turn the shaft Q in one direction or the other. The cam-frame Y has circular portions Y' and Y² and an eccentric or cam portion Y³, while the cam-frame Z has curved portions Z' and Z² and a short cam portion Z³. It will be noticed that throughout the several cam-frames the cam portion is intermediate the curved portions and the several frames moving together will operate their respective slide-rods to secure the desired result. Thus if the parts be as shown in full lines, Fig. 1, the cam-frame Y will have operated the rail-sections C into alinement with the rails A and the cam-frame X will have operated its sliding lock-plates E on the rails A into engagement with the rail-sections C to lock the same firmly in position. If now it is desired to adjust the swinging rail-sections C into line with the rail B, the lever U² may be swung over, operating first to free the lock-plates E of the rail-sections A from engagement with the rails C, after which the cam-frame Y will turn the rails C into alinement with the rails B, and after that the cam-frame Z will operate through the connections before described to adjust the sliding lock-plates of the rail-sections B into engagement with the rails C to lock the latter into alinement with the rails B. The construction is simple and operates effectively for the desired purpose.

While the rails A and B are shown crossing each other at a right angle, it will be understood they may be arranged at a different angle without departing from the principles of my invention.

Having thus described my invention, what I claim, and desire to secure by Letters Patent, is—

1. The combination substantially as herein described of a pair of tracks crossing each other and having the main rails terminating on the opposite sides of the point of crossing, rail-sections swinging within the crossings into alinement with the fixed or main rails of the different tracks, slide-rods, pitmen connecting the slide-rods with the swinging rail-sections whereby to swing the latter, locking-plates movable along the fixed rail-sections into and out of engagement with the swinging rail-sections, the main slide-rod for operating the locking-plates of the rails of one track, the slide-rod parallel with said first slide-rod, and the cross-rods connected with and operated by the latter slide-rod for operating the locking-plates of the rails of the other track, and means for operating the main slide-rods substantially as set forth.

2. The combination in a railroad-crossing of the fixed rail-section, a swinging rail-section, a chair-plate for the fixed rail-section

having a longitudinal undercut groove and a stop-flange, and a sliding lock-plate sliding along the fixed rail-section into and out of position to secure the swinging rail-section in 5 line with the fixed rail-section substantially as set forth.

3. The combination in a railroad-crossing with the fixed rail-section and a swinging crossing-section turning into and out of alignment therewith, of a sliding lock device movable along one of said rail-sections into engagement with the other rail-section and adapted to embrace the latter substantially as set forth.

15 4. The combination of the swinging rail-section, the turn-table therefor having a clamp securing the base of such section and having a circular base tapered as described, and the seat-plate for said turn-table having an undercut recess to receive said tapered base substantially as set forth.

5. The combination of the cross-tracks, slide-rods extending parallel with the rails of one of said tracks, swinging rail-sections operated by such slide-rods and crank-shafts for operating the slide-rods, a second set of slide-rods parallel to the first rods, lock devices operating on the rails parallel with such second set of slide-rods and connected with 25 30 and arranged for operation by such slide-rods, a crank-shaft connected with the second set of slide-rods, a third slide-rod parallel with the said first and second set of slide-rods, cross slide-rods at a right angle to the third slide-rod and arranged for operation thereby, lock devices operating on the rails parallel

with the slide-rods and arranged for operation thereby, a crank-shaft for operating the third slide-rod, and operating devices connected for joint operation and arranged to 40 operate their respective crank-shafts substantially as and for the purposes set forth.

6. In an apparatus substantially as described the combination with the fixed and swinging rail-sections and the lock devices 45 therefor of the cam-frames connected for joint operation and having the circular and cam or eccentric portions and intermediate mechanism between such cam-frames and the swinging rail-sections and lock devices which they 50 respectively operate substantially as set forth.

7. The combination with the slide-rod and a pair of sliding locking devices for operation thereby of a lever connecting the slide-rod directly with one of the slide devices, a lever 55 connected at one end with the other sliding device and an intermediate slide-rod and lever between such lever and the first slide-rod substantially as set forth.

8. The combination of the fixed and swinging rail-sections, the lock devices for the swinging sections, the cam-frames arranged side by side and connected for joint operation, and connections between said cam-frames and the locking devices and the swinging rail-sections 60 65 which such cam-frames respectively operate substantially as set forth.
